[57] CLAIM

We claim the ornamental design for the scooter body, as shown and described.

DESCRIPTION

FIG. 1 is a side elevational view of a scooter body showing our new design; the scooter wheels and a portion of the scooter front upright, not part of the new design are shown in dashed lines. The non-illustrated side of the scooter body is similar to the illustrated side.

FIG. 2 is a rear perspective view of the scooter body depicted in FIG. 1; and,

FIG. 3 is a front perspective view of the scooter body depicted in FIG. 1.
